(57) **CLAIM**

We claim the ornamental design for an onion chopper, as shown and described.

DESCRIPTION

FIG. 1 is a top perspective view of an onion chopper, showing our new design.

FIG. 2 is a front elevational view of the onion chopper, the rear elevational view being a mirror image.

FIG. 3 is a left side elevational view of the onion chopper.

FIG. 4 is a right side elevational view of the onion chopper.

FIG. 5 is a top plan view of the onion chopper; and,

FIG. 6 is a bottom plan view of the onion chopper.
